UNITED STATES PATENT OFFICE.

HANS STÖPLER AND JULIUS NORD, OF UTRECHT, NETHERLANDS.

COMPRESSION APPARATUS FOR STOPPING BLOOD CIRCULATION.

1,279,784.

Specification of Letters Patent. Patented Sept. 24, 1918.

Application filed March 27, 1914, Serial No. 827,778. Renewed February 15, 1918. Serial No. 217,732.

To all whom it may concern:

Be it known that we, HANS STÖPLER and JULIUS NORD, subjects of the Queen of the Netherlands, and residing at Utrecht, Netherlands, have invented a certain new and useful Improved Compression Apparatus for Stopping Blood Circulation During Operations and Bleedings from Wounds, of which the following is a specification.

10. This invention relates to improvements in tourniquets.

The object of the invention is to provide an instrument of this character which is so constructed that painful pressure on parts 15 of the body adjacent the wound to which the instrument is applied will be avoided and which avoids the necessity of using a pad, the use of which is considered dangerous.

20. With this and other objects in view, the invention consists of certain novel features of construction, combination and arrangement of parts as will be more fully described and claimed.

25. In the accompanying drawings Figure 1 represents an end view of this instrument;

Fig. 2 is a longitudinal section thereof;

Fig. 3 is a transverse section of this instrument showing it applied.

30. In the embodiment illustrated this improved instrument comprises a cylindrical casing or drum *k* having a spool-shaped member mounted therein with the two end disks *a* and *a'* connected by a broad band *b*, and its spindle *c* disposed centrally between the two disks and revolvably mounted in said disks. This spindle projects at one end beyond the end of the casing *k* and is provided at said projecting end with an operating 40 handle *d*. On the other end of this spindle which projects beyond the disk *a* is mounted a fine toothed ratchet wheel *e*.

45. A spring pressed pawl *f* is mounted on the outer face of the disk *a* with its tooth positioned for engagement with the teeth of the ratchet wheel *e* and which is yieldably held in engagement with said ratchet teeth by means of a curved spring *f'* here shown made integral with the free end of the pawl *f*.

50. A press button *g* has a shank which extends through an aperture *k*² in the casing *k* and is connected with the free end of the spring *f'* as shown in Fig. 1 and is designed when pressure is exerted thereon, to press 55 said spring and force the pawl out of engagement with the teeth of the ratchet wheel

e thereby releasing the spindle *c* and permitting it to be turned freely in either direction by means of the handle *d*. Another spring *f''* is also positioned to engage the pawl *f* to hold it in yieldable engagement with the ratchet *e*. (See Fig. 1.)

55. A slide *k*³ is mounted on the shank of the button *g* outside the casing *k* and operates to secure said button in position.

A tape *h* is secured at one end to the spindle *c* and is adapted to be wound thereon, the free end thereof projecting normally through a slot *k'* in the side wall of the casing *k*. (See Fig. 3.) The free end 70 of this tape *h* has an inturned hook *h'* which is designed to engage an outturned hook *i'* secured to the free end of a tape *i*, the other end of which is fixed within the casing *k* in any suitable manner. (See 75 Fig. 3.)

When the free ends of the two tapes are interlockingly engaged by means of their co-operating hooks *h'* and *i'* they form a loop *h''*, the size of which may be varied by 80 winding or unwinding the tape *h* on the spindle *c* and which is held in adjusted position by the locking pawl *f* when engaged with the ratchet *e*.

In the use of this instrument, the tape *h* is 85 drawn out of the casing *k* a suitable distance to permit it to be passed around the member to which the instrument is to be applied, the spindle having first been released by exerting the pressure on the button *g*. After said 90 tape has been passed around the member to which the instrument is to be applied, the hook at the free end thereof is engaged with the co-operating hook *i'* on the fixed tape *i* and the handle is turned to wind up the tape 95 on the spindle *c*, the pawl *f* riding freely over the ratchet teeth of the wheel *e* during such turning and when the proper tension has been attained, the pawl will engage the teeth of said ratchet wheel and hold the 100 spindle against backward or unwinding movement, thereby reliably securing the tape around the member to which the instrument is applied. By constructing the casing *k* in cylindrical form and housing all of the 105 operating parts therein, a smooth surface is brought to bear on the body of the patient and consequently, painful pressure on adjacent parts is avoided. By so constructing this tourniquet, a uniform pressure is exerted and circulation of the blood through the arteries is impeded and finally stopped 110

without the use of a pad, and by dispensing with this pad, the instrument may be applied at any desired height above the wound.

By providing the peculiar locking mechanism described above the compressor will operate even should the spring *f* fail to act.

I claim as my invention:

1. In a tourniquet, a cylindrical casing having a slot in its side wall, a spool-shaped member revolubly mounted therein, a tape wound on said spindle with one end extending through the slot in said casing, a stationary tape disposed in said casing and having one end extending through said slot, the free ends of said tapes having coöperating fastening elements, means for locking said spool against turning in one direction, and a push button having a head outside of said casing for releasing said locking means.
2. In a tourniquet, a cylindrical casing having a slot in its side wall, a spool-shaped member revolubly mounted therein, a tape wound on said spindle with one end extending through the slot in said casing, a stationary tape disposed in said casing and having one end extending through said slot, the free ends of said tapes having coöperating fastening elements, means for locking said spool against turning in one direction, a push button having a head outside of said

casing for releasing said locking means, and means for securing said button in locking position.

3. In a tourniquet, a cylindrical casing, a spindle revolubly mounted therein and provided with disks at its opposite ends, said spindle being loosely mounted in said disks and projecting at its opposite ends beyond the outer facing thereof, a handle on the outer end of said spindle, a ratchet wheel secured to the inner end thereof beyond the inner disk, a spring-pressed pawl positioned to engage said ratchet wheel, a pawl-releasing button connected with the spring thereof and having its head disposed outside said casing, a tape fixed at one end to said spindle and having its other end extending through a slot in said casing, and a tape fixed at one end in said casing with its other end extending through the slot in the casing, the free ends of said tapes being provided with coöperating fastening elements.

In testimony whereof we affix our signatures in presence of two witnesses.

HANS STÖPLER.
JULIUS NORD.
